C. A. Snowdon

UNITED STATES PATENT OFFICE.

WILLIAM H. H. SPRADLIN, OF SOUTH FORK, MISSOURI.

SORGHUM-FURNACE.

SPECIFICATION forming part of Letters Patent No. 390,713, dated October 9, 1888.

Application filed January 25, 1888. Serial No. 261,883. (No model.)

To all whom it may concern:

Be it known that I, WILLIAM H. H. SPRADLIN, a citizen of the United States, residing at South Fork, in the county of Howell and State of Missouri, have invented a new and useful Improvement in Sorghum-Furnaces, of which the following is a specification.

My invention relates to an improvement in furnaces for evaporating the juices of sorghum or sugar-cane; and it consists in the peculiar construction and combination of devices, that will be more fully set forth hereinafter, and particularly pointed out in the claims.

In the accompanying drawings, Figure 1 is a side elevation of a furnace embodying my improvement. Fig. 2 is a vertical longitudinal sectional view of the same. Fig. 3 is a vertical transverse sectional view of the same.

A represents the furnace, which is rectangular in shape, is made of metal or other suitable material, and has its front end depressed to form a fire-box, B, in opposite sides of which are secured fire bricks or plates C, to retain the heat and prevent the sides of the fire-box from being burned out. In the bottom of the fire-box is a grate, D, which has its inner end provided at its corners with projecting trunnions E, which trunnions are journaled in the lower ends of depending brackets F, which are secured to the outer sides of the furnace.

Under the front end of the furnace is pivoted a lug, G, which is adapted to be turned, so as to cause the shorter end to engage the free edge of the grate, and thereby support the latter in a horizontal position in the bottom of the fire-box. By swinging the said lug outward the shorter arm may be caused to disengage the grate, and thereby cause the latter to drop and discharge the burning fuel from the fire-box, as will be readily understood.

On the front end of the furnace is a door, H, through which fuel is fed to the fire-box.

I represents a series of vertical supporting-legs, which are attached to the corners of the furnace and support the same at a suitable distance above the ground. The front corners of the furnace are provided with a pair of projecting handles, K, and the lower ends of the supporting-legs at the rear corners of the furnace are provided with rollers or casters L. By this construction the operator is enabled to

grasp the handles K, raise the front end of the furnace from the ground, and wheel the same to any desired place, as will be readily understood.

M represents a horizontal partition or diaphragm, which is arranged in the furnace at a suitable distance above the bottom thereof, and which extends from near the rear end of the furnace to within a suitable distance of the fire-box, as shown. This horizontal diaphragm or partition divides the rear portion of the furnace into two horizontal flues, N O, the former of which is below the diaphragm or partition, and the latter of which is above the same.

P represents a transverse plate, which is secured over the rear end of the furnace, and is provided with a smoke-pipe, R, through which the products of combustion escape.

S represents a damper, which is journaled at its rear side in the sides of the furnace at a point on a level with and in close proximity to the front end of the diaphragm or partition M. This damper has a crank, P', by means of which it may be turned downward, as illustrated in solid lines in Fig. 2, so as to bear upon the bottom of the furnace, and by means of which the said damper may be turned upward to engage the lower side of the evaporating-pan a, as shown in dotted lines in the said figure. The crank is further provided with a ratchet-wheel, U, which is engaged by a pawl, V, and is thereby adapted to secure the damper S in any desired position.

W represents a damper, which is arranged at the rear end of the diaphragm or plate M, and has trunnions which are journaled in the sides of the furnace. The said damper is further provided with a crank, X, by means of which it may be either turned downward on the diaphragm M, as shown in dotted lines in Fig. 2, or it may be turned up against the upper side of the furnace, as shown in solid lines in the said figure, so as to close the rear end of the flue O.

The sides of the furnace above the level of the diaphragm M, and on opposite sides of the same, are provided with openings Y, which may be either covered or uncovered by slides Z, which work in suitable horizontal guides, A', on opposite sides of the furnace.

The operation of my invention is as follows:

When the dampers S and W are turned to the positions indicated in solid lines in Fig. 2, so as to close both ends of the flue N, the products of combustion and the caloric currents 5 pass rearwardly over the diaphragm M and are brought directly in contact with the bottom of the evaporating-pan, so as to heat the latter to the maximum degree. When it is desired to partially cool the evaporating-pan to 10 prevent its contents from burning, the damper S is turned upward and the damper W is turned downward and forward, as shown in dotted lines in Fig. 2, so as to cut off communication between the fire-box and the flue O and 15 open communication between the said fire-box and the lower flue, N, and thereby cause the caloric currents and products of combustion to pass through the said flue N under the diaphragm M and at such a distance below the 20 bottom of the evaporating-pan that the latter will be heated only to a minimum extent. In the event that it should be necessary to rapidly cool the evaporating-pan to prevent its contents from burning, this may be accomplished 25 by turning the dampers to a position thus described, and by opening the slides Z, so as to uncover the openings Y in the sides of the furnace, and thus admit fresh cold air to the flue O between the bottom of the evaporating-pan and the top of the diaphragm M. If necessary to do so, the fire may be entirely discharged from the furnace by turning the lever 30 or catch G, so as to disengage the grate and cause the latter to tip or drop downward, as 35 hereinbefore described.

A furnace thus constructed is extremely cheap and simple, and is provided with ample means for so thoroughly regulating the heat that the contents of the evaporating-pan may

be entirely prevented from being scorched or 40 burned.

Having thus described my invention, I claim—

1. The combination of the furnace having its front end depressed to form a fire-box, the 45 pan a, resting on the furnace and forming the top of the same, the horizontal partition arranged in the rear portion of the furnace and forming the flues N O, the damper S, pivoted between the sides of the furnace at the front 50 end of the partition and adapted to be turned down against the bottom of the furnace and up against the bottom of the pan a, and the damper W, pivoted between the sides of the furnace at the rear end of the partition, as and 55 for the purposes set forth.

2. The combination of the furnace having the fire-box B at its front end and the openings Y in its sides, near its rear end, the slides Z, mounted on the sides of the furnace and adapted 60 to close said openings Y, the plate P on the upper side of the furnace at its rear end and having a smoke-exit, the horizontal partition in the rear portion of the furnace just below the openings Y and forming the flues N O, the 65 vertically swinging damper S, pivoted between the sides of the furnace at the front end of the partition, and the damper W, pivoted between the sides of the furnace at the rear end of the partition, as specified.

In testimony that I claim the foregoing as my own I have hereto affixed my signature in presence of two witnesses.

WILLIAM H. H. SPRADLIN.
